UNITED STATES PATENT OFFICE.

JAMES G. GREENE, OF ELIZABETH, NEW JERSEY, ASSIGNOR TO THE SINGER
MANUFACTURING COMPANY OF NEW JERSEY.

PLAITING ATTACHMENT FOR SEWING-MACHINES.

SPECIFICATION forming part of Letters Patent No. 480,260, dated August 9, 1892.

Application filed April 18, 1892. Serial No. 429,616. (No model.)

To all whom it may concern:

Be it known that I, JAMES G. GREENE, a citizen of the United States, residing at Elizabeth, in the county of Union and State of New Jersey, have invented certain new and useful Improvements in Plaiting Attachments for Sewing-Machines, of which the following is a specification, reference being had therein to the accompanying drawings.

- 10 My invention relates to that class of sewing-machine attachments adapted to form folds or plaits in fabrics and to guide the same to the stitch-forming mechanisms of sewing-machines; and it has for its object to provide
15 a simple and convenient attachment of the class referred to whereby two reversely-laid folds or plaits may be simultaneously produced in a piece of goods and may be held and guided to a two-needle sewing-machine, which
20 will thus simultaneously stitch both folds or plaits.

In carrying my invention into effect I provide, in connection with a stationary guide or folder arranged centrally in front of the needles of the machine and having a top plate or part forming two overhanging guiding portions or edges, two swinging plait-forming blades or knives arranged to enter beneath the overhanging portions or edges of the stationary guide, and thus in connection therewith to form two reversely-laid plaits or folds, which are properly held and guided to the needles of the sewing-machine. The swinging plaiting blades or knives are carried by
25 pivoted arms, which are preferably so connected together that the movement of one into or out of working position will cause a similar movement of the other.

In the accompanying drawings, Figure 1
40 shows in front side elevation a portion of a sewing-machine with my invention applied thereto, the parts being in working positions. Fig. 2 is a similar view, but with the plaiting-blades swung outward for the insertion of the work. Fig. 3 illustrates my device as seen from the front end of the sewing-machine head. Fig. 4 is a plan view of the folding-guide and plaiting-blades, with the latter in

the positions shown in Fig. 1. Fig. 5 is a top view of the stop which holds the plaiting-blades out of working position, one of the plaiting-blade-carrying arms being shown in cross-section. Fig. 6 is a plan view of a modified form of my invention with the parts in working position, and Fig. 7 is a similar view 55 with the plaiting-blades swung aside for the insertion of the work. Fig. 8 illustrates this form of my invention as seen from the front end of the head of the machine; and Fig. 9 is a view, looking from the front side of the 60 sewing-machine, of the plaiting-blades in the positions shown in Fig. 6. Fig. 10 illustrates the work to be made by my device.

A denotes a portion of the arm of a sewing-machine, and B a part of the work-plate 65 thereof.

Referring now more particularly to the preferred form of my invention, (shown in Sheet 1 of the drawings,) a denotes a plate or small bracket secured to the lower part of the depending portion or head A' of the arm A, and to the said plate or bracket are pivoted at their upper ends two arms or levers C, carrying at their lower ends the swinging plaiting-blades c. The arms C are preferably connected together by intermeshing teeth d, formed thereon adjacent to their pivots, and by a spring e, which has a tendency to force them together.

To limit the inward movements of the arms 80 C under the stress of the spring e, so as to hold the plaiting-blades in proper working position, I preferably provide a stop device consisting, as herein shown, of a bar or projection f, interposed between the said arms C 85 and engaged by projections thereon consisting, preferably, of adjustable screws g, arranged to abut against said bar or projection f.

To hold the plaiting-blades out of working 90 position, as shown in Fig. 2, when the work is to be inserted, I provide a retaining-arm H, suspended from the head A' and having a shoulder at h, which engages one of the arms C, as shown in Figs. 2 and 5, and thus holds 95 said arm outward until it is released from said

shoulder, which is done either by pressing the arm H inward (said arm being preferably a spring-arm or being spring-supported, as by the spring-hanger h') or by springing the arm C outward away from the retaining-arm. When the arm C is swung outward, it rides up a slight incline at h' on the arm H until it comes opposite the shoulder h, when it springs into engagement with said shoulder. The needle-bar I carries two needles i, and the presser-foot J is provided with two holes for the passage of said needles, and arranged centrally in front of said needles is the stationary guide K, which co-operates with the plaiting-blades c. The said guide K is preferably attached to the work-plate B, and, as herein shown, said guide consists of a small block having vertical guiding-faces on its opposite sides, said block being surmounted by a plate k, which overhangs the same on both sides to form projections, beneath which the plaiting-blades extend in making the reversely-laid folds or plaits. The width of the plate k will determine the distance between the plaits or folds m, Fig. 10, being made, and for varying the work interchangeable plates of different widths will be provided. The plaiting-blades, as also the plate or top plate or portion of the guide K, are preferably formed with rounded or bluntly-pointed forward ends to assist in the formation of the folds or plaits in the work as the latter is guided forward to the needles.

In the form of my invention shown in Figs. 6, 7, 8, and 9 of the drawings the plaiting-blades c' are carried by horizontal arms C', secured by vertical pivot-screws to a bracket a', attached to the head A', and which is shown as being provided with a steadyng portion or sleeve a'', surrounding the presser-bar J'. The arms C' are shown as being provided with intermeshing teeth d', as in the preferred form of my invention, and are connected by a coil-spring e', which draws them together until their inward movements are limited by stops f', arranged in front of their pivots. When the said arms C' are thrown outward a little farther than shown in Fig. 7, the spring e' will be slightly rearward of the centers of the pivots of said arms and will then hold said arms separated, the outward movements of said arms being limited by the stops f'' rearward of the arms, which stops will then be in contact with each other.

In the use of my attachment the plaiting-blades are swung outward, as shown in Figs. 2 and 7, and a piece of fabric to have the reversely-laid plaits formed therein is then laid upon the stationary guide K and the plaiting-blades are swung inward, thus forcing portions of the fabric beneath the overhanging edges of said guide and forming two reversely-laid plaits or folds. The work is then drawn forward beneath the needles, and, the presser-foot being lowered, the machine is started,

when the work will be drawn forward by the feed of the machine and the reversely-laid plaits or folds of any desired length will be formed and stitched, as will be understood.

My device is particularly adapted for use in forming the central plaits of shirt-bosoms, but may be employed for any other kinds of work in which it is desired to simultaneously fold and stitch two reversely-arranged plaits.

Having thus described my invention, I claim and desire to secure by Letters Patent—

1. In a plaiting attachment for sewing-machines, the combination, with a stationary guide arranged centrally in front of the needles and having vertical guiding-faces on its opposite sides and overhanging edges projecting laterally from the sides of said guide beyond said vertical guiding-faces, of two swinging plaiting-blades placed on opposite sides of said guide and normally extending beneath said overhanging edges and pivoted arms by which said blades are carried.

2. In a plaiting attachment for sewing-machines, the combination, with a central guide having overhanging edges, of two swinging plaiting-blades and two connected pivoted arms by which said blades are carried, said arms having intermeshing portions, so that a movement of one will cause a simultaneous movement of the other.

3. In a plaiting attachment for sewing-machines, the combination, with a stationary guide arranged centrally in front of the needles and having overhanging edges, of two swinging plaiting-blades on opposite sides of said guide and normally extending beneath said overhanging edges, pivoted arms by which said blades are carried, a spring for forcing said arms toward each other, and a stop device for limiting their inward movements.

4. In a plaiting attachment for sewing-machines, the combination, with a central guide having overhanging edges, of two swinging plaiting-blades arranged to enter beneath said overhanging edges, two pivoted arms by which said blades are carried, a spring for forcing said arms toward each other, and adjustable stops for limiting their inward movements and for determining the positions of the plaiting-blades relative to the overhanging edges of the said guides.

5. In a plaiting attachment for sewing-machines, the combination, with a stationary guide arranged centrally in front of the needles and having vertical guiding-faces on its opposite sides and overhanging edges projecting laterally from the sides of said guide beyond said vertical guiding-faces, of two connected swinging arms carrying plaiting-blades arranged on opposite sides of said guide and normally entering beneath said overhanging edges and a retaining device to

hold said plaiting-blades separated when they are swung outward from said guide for the insertion of the work.

6. The combination, with the central guide 5 K, having overhanging edges, of the pivoted arms C, carrying the plaiting-blades c, arranged to enter beneath said edges, said arms having the intermeshing teeth d and the stop-screws or projections g, the stop-bar or pro-

jection f, interposed between said arms, and 10 the spring e, serving to force said arms toward each other.

In testimony whereof I affix my signature in presence of two witnesses.

JAMES G. GREENE.
